V. JANSEN.
PAINTER'S STRIPING MECHANISM.
APPLICATION FILED AUG. 18, 1919.

Patented June 1, 1920.

Inventor:
VICTOR JANSEN,

By Mack and Lichtenberg
Attorneys

UNITED STATES PATENT OFFICE.

VICTOR JANSEN, OF LOS ANGELES, CALIFORNIA.

PAINTER'S STRIPING MECHANISM.

1,341,803.

Specification of Letters Patent.

Patented June 1, 1920.

Application filed August 18, 1919. Serial No. 319,827.

To all whom it may concern:

Be it known that I, VICTOR JANSEN, a citizen of the United States, residing in the city of Los Angeles, county of Los Angeles, 5 and State of California, have invented certain new and useful Improvements in Painters' Striping Mechanism, of which the following is a specification.

This invention embodies improvements in 10 my invention as shown and described in Letters Patent No. 1,305,545, issued to me June 3, 1919.

The salient objects of my present invention are to provide in a device of the character referred to improved means for storing air under pressure within the device for use in forcing the paint from the reservoir thereof to and through the brush; to provide in connection therewith simple and practical valve 15 mechanisms for controlling the air supply and its use as required; to provide an improved device of the character referred to which can be used in any position and in which the flow of the paint can be kept uniform at all times. Other features of improvement will appear from the following description of the same, taken with the accompanying drawings, thereof, in which,—

Figure 1 is a plan of my improved device; 30 Fig. 2 is a front end view thereof;

Fig. 3 is a longitudinal sectional view therethrough;

Fig. 4 is a side elevation with parts shown in section;

Fig. 5 is a cross sectional view taken on line 5—5 of Fig. 3;

Fig. 6 is a rear end view; and

Figs. 7 and 8 are details.

Referring in detail to the drawings, 1
40 designates a body of cylindrical form with an angle portion 2, adapted to have telescoped thereover a tubular handle 3, having along its under side a smaller tubular portion 4, in which is a plunger 5, normally pressed toward the body 1 by means of a spring 6. The forward end of said plunger carries a holding latch 7, adapted to fit into notches 8, in the edge of a collar 9 around said body, whereby said collar can be adjusted to different positions to hold a guide bar 10, adjustably secured thereto as indicated by means of a thumb screw 11. Said bar 10 is provided with an adjustable finger 10^a. The plunger 5 is provided with an operating pin 5^a, by means of which said

plunger can be pulled back at will to release said collar 9.

Mounted in the tubular portion 3, is an expandible air container or bellows, 12, provided at its forward end with a nozzle 13, 60 projecting through the end wall 2^a, of the body extension 2, as clearly indicated in Figs. 3 and 4. The rear end of said air container 12 is provided with a cup 14 adapted to hold the end of a coiled spring 15, the other end of which bears against an end cap 3^a, of the tubular handle portion 3. A screw ring 16 is provided in said cap 3^a, and is connected to the end of the expandible air container, or bellows, 12, by means of a cord 65 or chain 17, for extending said bellows for the purpose of filling it with air, in a manner hereinafter referred to.

The body 1 is provided in its upper end with a screw plug 18, having a hexagonal head, 18^a and having a central bore therethrough, as shown. A valve sleeve 20 of less diameter, is slidably mounted through said plug 18 whereby to admit air through said plug around said sleeve, and is provided at its outer end with a head 20^a, and at its inner end with a valve member 20^b, which closes the inner end of said screw plug 18. This controls the air inlet to the bellows. A valve pin 19 is slidably mounted 75 through said sleeve 20, said head 20^a, and said screw 20^b, and is provided with a valve 21, secured thereto, with a spring 22 bearing at one end against the valve member 20^b, on the sleeve 20, and at its other end bearing 80 against the valve 21. The valve 21 seats against the end wall 1^a of the body 1, to control the passage of air therethrough. Said valve pin 19 also extends through said wall 1^a and operates as a needle valve in a 85 tubular boss 23, projecting into a reservoir body 24, mounted on the end of the body 1, as indicated in Figs. 3 and 4. Said reservoir is provided with a closure 25, as indicated. It is also provided therein with shot 90 S, or other equivalent means, to fill up the corner of the reservoir to facilitate the discharge of more of the paint from said reservoir, as will be readily understood.

A brush 26, having a tubular center 27, 105 which registers with the boss 23, is secured to the reservoir body 24, by means of a bayonet collar 28, as indicated, thus making it possible to use different brushes with the same instrument.

An operating lever 29 is pivotally mounted on the handle portion 3 of said device, as at 30, with one end connected with the valve pin 19 by means of a slot and neck 5 connection, a well known construction, and near its other end provided with an adjustment stop screw 31, for determining the distance said lever 29 can be depressed and consequently, the distance said valve pin 19 can 10 be moved to open the valve 21, to admit air into said reservoir 24.

The use and operation of my invention may be briefly described as follows: Paint is put into the reservoir member 24 after the 15 closure 25 is removed. The screw ring 16 is removed and pulled out to extend the air container 12. At the same time the head 20^a is pressed inwardly by the thumb to move the sleeve 20 and the valve 20^b inwardly so 20 that air can pass through the screw plug 18, around said sleeve 20, and into the angle member 2 and into said bellows 12 as it is extended. The spring 15, of course, is compressed by this action. When the bellows 25 is full, the head 20^a is released and is moved outwardly by the spring 22, closing the valve 20^b. The screw ring 16 can then be put back into place with its chain within the handle 3. The instrument is now 30 charged with paint and with air and ready for use. In use, it is only necessary to press the lever 29 with the thumb, according to the adjustment of the stop screw 31, to admit air past the valve 21 and into the reservoir 24 for forcing the paint out through the boss 23 and the brush 26. The thickness of the paint determines the air pressure needed to force the paint properly out through the brush. When the air container 12 has been 40 compressed by the spring 15, and all the air has been discharged therefrom, it is only necessary to again extend it, as before.

I am aware that changes in details can be made in my invention as here shown for 45 illustrative purposes, without departing from the spirit thereof, and I do not, therefore, limit the invention to the showing made, except as I may be limited by the hereto appended claims.

50 I claim:

1. A device of the character referred to, comprising a body provided therein with a paint reservoir and an independent air reservoir adapted to hold air under pressure, a brush, a valve controlling the flow of paint from the paint reservoir to said brush, a valve controlling the flow of air under pressure to said paint reservoir, and means for operating both of said valves 55 together to admit air to the paint reservoir, and to admit paint to the brush.

2. In a device of the character referred to, in combination, a body having therein a paint reservoir and a separate air reservoir, with a communicating passageway 60

therebetween, a valve for controlling said passageway, a brush, valve-controlled means for feeding paint from said paint reservoir to said brush, means for supplying air under pressure to said air reservoir, and manually operable means for simultaneously opening the valve between the air reservoir and the paint reservoir, and the valve for controlling the passage of paint from the paint reservoir to said brush. 70

3. In a device of the character referred to, a body having a reservoir therein for paint, a brush attached thereto in communication with said reservoir, a separate air container within said device, means for supplying the same with air under pressure, and valve controlled means for feeding said air under pressure to said paint reservoir as needed to force paint therefrom to said brush. 80

4. In a device of the character referred to, a body having a reservoir therein for paint, a brush attached thereto in communication with the said reservoir, a separate air reservoir within said device, means for supplying the same with air under pressure, valve controlled means for feeding air under pressure to said reservoir as needed to force paint therefrom to said brush, a valve for controlling the flow of paint to said brush, and means for operating said valves. 90

5. In a device of the character referred to, a body of angular form, one part thereof having a paint reservoir therein and the other part having an air container therein, a brush connected with said reservoir to receive paint therefrom, means for supplying air under pressure to said air container, valve mechanism for controlling the supply of air to said air container, and valve mechanism for controlling the flow of air to said reservoir and the flow of paint to said brush. 100

6. In a device of the character referred to, a body of angular form, one part thereof having a reservoir therein for paint, and the other part having an expandable air container therein, means for holding a brush in communication with said reservoir to be fed therefrom, a valve for controlling the flow of paint from said reservoir to said brush, valve controlled means for supplying air from said air container to said reservoir for forcing paint therefrom to said brush, and means for expanding said air container to fill the same with air. 110

7. In a device of the character referred to, a body of angular form, one part of which is provided with a paint reservoir and the other part of which is provided with an air container, means for filling said air container with air under pressure, valve means for controlling the admission 120

- of air to said container, valve means operable at will to admit air from said container to said paint reservoir, and a brush connected to said body to receive paint from said paint reservoir.
8. In a device of the character referred to, in combination with a brush and means for holding and supplying paint to said brush, an expansible air container for holding and supplying air to said device, a valve controlling the supply of air to said air container, and a manually operable valve
- 5 for controlling the flow of air from said container to said paint holding means, said valves being provided on said device with 15 means for convenient operation during the use of the device, substantially as shown.
- Signed at Los Angeles, county of Los Angeles, and State of California, this 13th day of August, 1919.
- VICTOR JANSEN.
